UNITED STATES PATENT OFFICE

2,415,761

OPEN-HEARTH FURNACE

Edwin R. Richards, Chicago, Ill.

Application April 2, 1942, Serial No. 437,435

5 Claims. (Cl. 122—6)

1

This invention relates to specific features of construction and arrangement of open hearth furnaces and aims particularly to provide a water-cooled support for the upper parts of the front walls and arches located over the charging door openings of the open hearth furnace.

The foregoing and other features of the invention will be apparent from the following specification, the accompanying drawings and the appended claims.

In the drawings:

Figure 1 is a view of an open hearth furnace, partly in elevation and partly in section looking from the tapping side of the furnace toward the charging doors;

Figure 2 is a fragmentary horizontal section on line II—II of Figure 1;

Figures 3 and 4 are enlarged cross sectional views through the charging door openings of a conventional open hearth furnace illustrating the destructive action which the present invention aims to minimize;

Figures 5 and 6 are views showing coolant boxes located between the arches of the charging door openings in the front wall of the furnace and constituting an important characteristic of the present invention; and

Figure 7 is a front elevation of a portion of the furnace showing one charging door opening and two adjacent cooling boxes of the present invention incorporated in the front wall.

Referring in detail to the drawings, Figure 3 shows a typical cross section through the charging door of a conventional open hearth furnace. The door opening is indicated at 10, the conventional arch over the opening at 12, and the usual roof at 14. The front wall, indicated at 16, according to the practice prior to my invention, has frequently required premature replacement for the reason that it becomes eroded or worn away more rapidly than the upper part, thus leaving it unsupported. To alleviate this condition it is a common practice as the front wall becomes worn away or eroded to provide support by piling up a mass of chrome ore such as indicated by the stippling at 18 in Figure 4. This figure shows an irregular full line 20 suggestive of the manner in which the front wall 16 becomes eroded. The dotted line 22 in Figure 4 corresponds to the similarly identified full line 22 in Figure 3, which shows the original inner surface of the front wall of a new furnace.

The expedient of piling up a body of chrome ore such as shown at 18 in Figure 4 is frequently resorted to by those skilled in the art to prolong

2

the front wall life of a furnace, but nevertheless in an inordinately short time furnace front walls frequently fail and require shutting down of the furnace for the purpose of rebuilding the same.

It is known to those skilled in the art that open hearth furnaces have a relatively short life and it is a matter of general knowledge to those familiar with the steel industry that production schedules are largely dependent upon the useful life of the various furnaces in a given battery of the open hearths.

It is a particular feature of the present invention to provide means for prolonging the life of the furnace front wall which is one of the most vulnerable parts of an open hearth furnace. To this end I provide a device for supporting the upper part of the brickwork of the front wall and arches over the charging door openings of the furnace, this device taking the form of either welded or cast metal tank-like containers in which sufficient water or other coolant is caused to circulate in a manner to prevent early destruction of the structure. In the drawings, these tank-like containers are indicated at 24. They are in the nature of hollow box-like structures with top and bottom walls 26 and 28, front and rear walls 30 and 32, and end walls 34 and 36. The latter walls are obliquely inclined in opposite directions so as to suit the inclination of the obliquely inclined end bricks of the arches 12 usually provided over the door openings 10. For convenience of illustration, the containers are shown as integral castings, but it will be understood that each can be formed of several metal plates welded to one another. Each container is supplied with a suitable coolant such as water from a branch pipe 40 communicating with a supply main 42, there being a control valve 44 in each of the branch pipes. Each container also connects with an outlet pipe 46 which leads to a suitable drain or sump tank 48. Distributor pipes 50 located within the containers are arranged to discharge coolant in the direction of the arrows of Figure 7 toward the end walls 34 and 36. Thus there is constantly supplied a cooling medium in the region of the furnace front wall which is most vulnerable to attack by the intense heat of the furnace and by the erosive action of the flame and combustion products constantly passing through the furnace.

Each container is provided with suitable attaching bars 52 which are adapted to be secured to plates 54 which in turn are secured to the buck stays 56 constituting part of the conventional framework of the open hearth furnace.

With the water-cooled containers located in the upper portion of the brick wall and between the arches 12 over the door openings, the arches are supported independently of the lower part of the wall. This is advantageous for it permits the lower part of the wall to be patched or reinforced by covering with suitable temperature and slag resisting materials or the lower part of the wall can be entirely replaced without disturbing the upper part.

The disclosed structure is also of advantage for the reason that the cooling effect of the containers at the zones of maximum wear or erosion give an added support which will greatly prolong the life of the front wall and thus reduce maintenance costs and thereby increase steel production by reducing the frequency of shut-downs for the purpose of making repairs. The exact shape and size of the coolant containers will depend upon the furnace in which they are to be installed and the manner in which the wall they are to support is normally burned away or eroded. However, it is regarded to be particularly important to provide the coolant containers in the region between each of the several charging doors 10 at an elevation approximately level with the upper portion of such door openings. This is for the reason that when so located the containers will serve to adequately support the roof arches over the door openings for a much longer time than such arches will be properly supported in the absence of such coolant containers.

Various modifications may be made by those skilled in the art without departure from the invention as defined in the appended claims.

I claim:

1. In an open hearth furnace having a front wall with a plurality of charging door openings therein, arches over the door openings and a plurality of coolant containers embedded in the furnace front wall in the horizontal level between the arches over said door openings, said arches at their ends bearing directly against said containers.

2. In an open hearth furnace having a front wall with a plurality of charging door openings therein, respective brick arches over said openings, respective hollow metallic coolant containers embedded in said furnace wall spanning the space between the respective arches, each container having obliquely inclined end walls against

which the ends of said arches make direct contact.

3. In an open hearth furnace having a front wall with a plurality of charging door openings therein, respective arches over said openings, respective hollow metallic containers embedded in said furnace wall between the respective arches, each container having obliquely inclined end walls against which said arches take a direct bearing, means for supplying a coolant to each of said containers, and respective means for discharging the coolant from the containers, each container having therein a pipe adapted to direct the coolant toward said oblique walls.
- 5 10 15 20 25 30 35 40 45
4. In an open hearth furnace having a front wall with a plurality of charging door openings therein, respective arches over said openings, respective hollow coolant containers embedded in the upper part of the furnace wall in a region between horizontal planes coincident with the upper and lower extremities of said arches, each container having portions supporting said arches, and metallic supports to which said containers are secured, the whole structure being constructed and arranged to facilitate the making of repairs to the lower part of the front wall, which usually fails first, without disturbing the upper part thereof.
5. In an open hearth furnace having a front wall with a plurality of charging door openings therein, respective arches over said openings, respective hollow coolant containers embedded in the upper part of the furnace wall, each container having portions supporting said arches, and fixed upright metal buck-stays to which said containers are secured, the whole structure being constructed and arranged to facilitate the making of repairs to the lower part of the front wall, which usually fails first, without disturbing the upper part thereof.

EDWIN R. RICHARDS.
